(57) **CLAIM**

I claim the ornamental design for a lamp simulating a UFO, as shown and described.

DESCRIPTION

FIG. 1 is a front elevational view of a lamp simulating a UFO showing my new design;

FIG. 2 is a top plan view thereof;

FIG. 3 is a bottom plan view thereof;

FIG. 4 is a top perspective view thereof; and,

FIG. 5 is a bottom perspective view thereof.
